UNITED STATES PATENT OFFICE.

FRED C. HOWE, OF NEW HAVEN, CONNECTICUT.

ADJUSTABLE LAMP.

1,142,964.

Specification of Letters Patent. Patented June 15, 1915.

Application filed August 7, 1914. Serial No. 855,537.

To all whom it may concern:

Be it known that I, FRED C. HOWE, a citizen of the United States, residing at New Haven, in the county of New Haven and State of Connecticut, have invented certain new and useful Improvements in Adjustable Lamps, of which the following is a specification, reference being had therein to the accompanying drawings.

10 My invention relates to a new and improved adjustable lamp of that type wherein in the lamp may be moved about a central point, and has for its object, among other things, to simplify and make more positive 15 the construction of this type of lamp with the fewest possible parts.

To these, and other ends, my invention consists in the adjustable lamp, having certain details of construction and combinations of parts, as will be hereinafter described and more particularly pointed out in the claims.

Referring to the drawings, in which like numerals of reference designate like parts in 25 the several figures, Figure 1 is a fragmentary side view of my improved lamp with the parts within which it is mounted shown in section; Fig. 2 is an end view thereof, partly in section; Fig. 3 is an enlarged side 30 elevation; and Fig. 4 is an enlarged fragmentary portion thereof, showing in detail the construction and arrangement of the pinion with the disk adjacent thereto.

My invention is particularly designed for 35 use upon automobiles, wherein it is desirable that the rays of light from the lamp may be thrown to any point within a limited zone about a central point, although not limited thereto, as its adaptability with other mechanisms and in other places is quite apparent.

In the drawings, the fixed part to which my improved lamp is connected is designated by the numeral 1, upon both sides of which are the collars 2—2. Within these 45 collars and the part 1 is rotatably mounted the shank 3 of the guide ball 4, through which is a straight slot 5 parallel to the axis of said shank.

Partly surrounding the guide ball 4, and 50 maintaining a movable contact therewith, is the cup 6, having an irregularly shaped opening 7 therethrough with a projecting lip 8 thereon parallel with and adjacent to the edge 9 of said opening. Fixed within 55 said opening is a plate 10, the outer edge of which is provided with teeth 11 and is se-

cured to the cup 6 by the bridges 12 so that the edge of the plate 10 containing the teeth 11 is substantially parallel with, the face 9 of the opening 7. Secured to the 60 cup 6 is the lamp body 19, within which is a lamp 20.

Rotatably mounted within the shank 3 is the shaft 13, having a hand wheel 14 upon one end and a pinion 15 upon its opposite end, the teeth of said pinion meshing into the teeth 11 and thereby moving the cup 6 about the center of the ball 4 as the shaft 13 is rotated, during which time the stud 16 travels in the slot 5 guiding the said cup 6. This engagement of the pin and slot always insures the retention of the cup 6 in any of its several positions. Endwise movement of the pinion 15, whereby it may become disengaged from the teeth 11, is prevented by the washer 17 that is rotatably mounted upon the screw 18, threaded into the shaft 13, and upon which the pinion 15 is fixed. The disk 17 rides against the lip 8, and thereby maintains and insures the intermeshing of the teeth 15 with the teeth 11. The thumb screw 21 is threaded through the spindle 3 and impinges against the shaft 13 so as to lock the shaft against rotation and hold the lamp in any of its several positions.

As minor changes and alterations can be made within my invention, I would therefore have it understood that I do not limit myself to the exact construction herein shown and described, but claim all that falls fairly within the spirit and scope of my invention.

Having described my invention, what I claim as new and desire to secure by Letters Patent, is:—

1. The combination with a globular member; of a cup member with an irregularly shaped opening therethrough partly surrounding said globular member and having a movable engagement therewith; a toothed plate within said opening; means for securing the same so that there is an open space around the entire edge thereof and inside the edge of the opening in said cup member, and means for moving said cup about said globular member, comprising a rotary shaft having a member thereon operatively engaging said toothed plate.

2. The combination with a globular member; of a cup member with an irregularly shaped opening therethrough partly sur-

- rounding said globular member and having a movable engagement therewith; a plate within said opening having teeth around the entire edge thereof; means for securing said 5 plate to said cup member, and means for moving said cup about said globular member, comprising a rotary shaft having a member thereon operatively engaging said plate.
- 10 3. The combination with a globular member; of a cup member with an irregularly shaped opening therethrough partly surrounding said globular member and having a movable engagement therewith; a toothed 15 plate within said opening; means for securing said plate to said globular member so as to have an opening entirely surrounding said plate and of substantially uniform width; means for moving said cup about 20 said globular member, comprising a rotary shaft having a member thereon operatively engaging said toothed plate.
4. The combination with a globular member; of a cup member with an irregularly shaped opening therethrough partly surrounding said globular member and having a movable engagement therewith; a plate within said opening having teeth in the edge thereof; means for moving said cup about 25 30 said globular member, comprising a rotary shaft having a member thereon operatively engaging said plate; and means, as a member adjacent to said pinion, for holding the same against endwise and lateral movement.
- 35 5. The combination with a globular member; of a cup member with an irregularly shaped opening therethrough and a shoulder parallel therewith partly surrounding said 40 globular member and having a movable engagement therewith; a toothed plate within said opening; means for moving said cup about said globular member, comprising a rotary shaft having a member thereon operatively engaging said toothed plate; and means for holding said pinion in engagement 45 with the teeth in said cup member.
- means with the teeth in said plate said member having contact with said shoulder.
6. The combination with a globular member; of a cup member with an irregularly shaped opening therethrough and a shoulder parallel therewith partly surrounding said globular member and having a movable engagement therewith; a plate within said opening having teeth in the edge thereof; means for moving said cup about said globular member, comprising a rotary shaft having a member thereon operatively engaging said plate; and means for holding said pinion in engagement with the teeth in said plate, said means comprising a disk having a rotary contact with said shoulder and held in relation to said pinion so as to prevent axial movement thereof.
7. In combination, a globular member having a substantially straight slot therein; of a toothed cup member; a member on said cup member projecting into said slot and having an operative engagement therewith; and means for moving said cup member about said globular member, said means comprising a rotary, toothed member having engagement with the teeth in said cup member.
8. In combination, a globular member having a substantially straight slot therein and a hollow shank connected therewith; of a toothed cup member; a member on said cup member projecting into said slot and having an operative engagement therewith; means for moving said cup member about said globular member, said means comprising a shaft rotatably mounted in said shank; and a pinion fixed thereto having a toothed engagement with teeth in said cup member.

In testimony whereof I affix my signature in presence of two witnesses.

FRED C. HOWE.
